THREE RING PENDANT

Henry Z. Nunez, 375 Broome St., New York, N.Y.

Filed May 16, 1963, Ser. No. 74,915

Term of patent 7 years

(Cl. D45—17)

FIG. 2 is a rear elevational view, and

FIG. 3 is a cross-sectional view taken on line 3—3 of FIG. 2.

I claim:

The ornamental design for a three ring pendant, substantially as shown.
